UNITED STATES PATENT OFFICE.

BERNARD T. LEVEQUE, OF WENHAM, MASSACHUSETTS, ASSIGNOR TO UNITED SHOE MACHINERY CORPORATION, OF PATERSON, NEW JERSEY, A CORPORATION OF NEW JERSEY.

STITCH-FORMING MECHANISM FOR SEWING MACHINES.

Application filed November 18, 1921. Serial No. 516,184.

To all whom it may concern:

Be it known that I, BERNARD T. LEVEQUE, a citizen of the United States, residing at Wenham, in the county of Essex and State 5 of Massachusetts, have invented certain new and useful Improvements in Stitch-Forming Mechanism for Sewing Machines; and I do hereby declare the following to be a full, clear, and exact description of the invention, such as will enable others skilled in 10 the art to which it appertains to make and use the same.

The invention relates to buttonhole sewing machines and more particularly to under 15 needle and looper mechanism for such machines.

The object of the invention is to provide an under needle and looper mechanism which is simple and durable in construction 20 and in which the motions are easy and accurately timed to secure a uniformly reliable action when operated at high speed. To this end, the invention comprises the features of construction and combination of 25 parts hereinafter described and referred to in the claims.

In the drawings Fig. 1 is a front elevation of the turret of a buttonhole sewing machine provided with the preferred form of 30 the invention, Fig. 2 is an elevation looking from the right in Fig. 1, Fig. 3 is a plan view of Fig. 2 and Fig. 4 is a sectional view on line 4, Fig. 2.

The stitch forming mechanism of that 35 class of machines to which the invention relates is usually mounted to rotate during the sewing of the buttonhole and comprises an upper needle mounted in a rotary support and an under needle and looper mounted 40 in a rotary turret. In the construction shown the under needle 2 and the looper 4 are mounted in a turret 6 which also carries the throat plate 8 through which the needles pass. The turret is rotated while 45 sewing about the eye or while sewing about the eye and about the bar end of the button-hole through a horizontal shaft 10 connected with the turret by beveled gears 12.

The under needle 2 is a straight eye-pointed needle and is secured in the upper 50 end of a needle bar 14 which is mounted to reciprocate in bearings on the turret. The path of movement of the needle is at an inclination to the path of movement of the upper needle 16 and is such that the under

needle passes up through the throat plate and presents a loop of under thread in position for the passage down therethrough of the upper needle. The needle bar is reciprocated by a lever 18 secured to a rock shaft 60 20 on the turret and connected by a link 22 with a collar 24 which is adjustably secured to the needle bar. The lever is oscillated to reciprocate the needle bar through a link 26 connecting the lever with the end of a lever 28 which is mounted on the frame of the machine, the link being located substantially in the axis of the turret. The looper 4 which takes a loop of thread from the upper needle and carries it into position 65 over the under needle is secured in the upper end of a vertical looper lever 30 mounted to swing about a pivot 32 which projects horizontally and transversely from the hub of a looper carrier lever 34. The looper lever is swung on its pivot to take the loop from the upper needle through a link 36 which connects the lower end of the lever with the needle actuating lever 18. The link 36 is made in two parts connected by a turnbuckle 38 by which the 70 length of the link may be adjusted to bring the looper into proper relation to the parts with which it cooperates. The looper carrier lever 34 is rocked to move the looper laterally by a three-cornered eccentric or cam 75 40 secured to a rock shaft 42 and arranged between the arms 44 at the lower end of the lever. The shaft 42 is actuated from the rock shaft 20 through a link 46 which connects an arm 48 secured to the rock shaft to an arm 50 secured to the shaft 42.

This under needle and looper mechanism is simple and durable in construction and the motions are easy and accurately timed 80 so that the mechanism is well adapted for efficient and uniformly reliable operation at high speeds. The straight needle bar and needle reciprocating at an inclination to the upper needle path contribute to the simplicity and compactness of the mechanism and also render the mechanism particularly well adapted for sewing fly bar buttonholes or 85 other classes of work in which the under needle must perforate the stock at certain points in the sewing of the seam and is therefore subjected to strains which curved needles are ill adapted to withstand.

While it is preferred to employ the specific construction and arrangement of parts 90 95 100 105 110

shown and described it will be understood that this construction and arrangement is not essential to the broader features of the invention and may be varied or modified as found desirable or best suited to the construction and mode of operation of the machine to which the invention is to be applied.

What is claimed is:

1. A stitch forming mechanism having, in combination, a looper, a vertical looper lever on the upper end of which the looper is carried, a carrier lever having a transverse pivot on which the looper lever is mounted, an actuator, a link connecting the actuator with the looper lever to swing the lever on its pivot and a cam operated from the actuator for rocking the carrier lever to move the looper lever transversely of its swinging movement.
2. A stitch forming mechanism having, in combination, a looper, a vertical looper lever on the upper end of which the looper is carried, a carrier lever having a transverse pivot on which the looper lever is mounted, an actuator, a link connecting the actuator with the looper lever to swing the lever on its pivot, a rock shaft provided with a cam connected to rock the carrier lever, and connections for rocking the shaft from the actuator.
3. A stitch forming mechanism having, in combination, a looper, a vertical looper lever on the upper end of which the looper is carried, a carrier lever having a transverse pivot on which the looper lever is mounted, an actuator lever, a link connecting the actuator lever to the looper lever to swing it on its pivot, a rock shaft having a cam engaging the carrier lever, an arm on the rock shaft, an arm moving with the actuator lever, and a link connecting the arms.
4. A stitch forming mechanism having, in combination, an under needle carrier, an ac-

tuator lever connected to reciprocate the needle carrier, a looper, a vertical looper lever on the upper end of which the looper is carried, a carrier lever having a transverse pivot on which the looper lever is mounted, a rock shaft provided with a cam for rocking the carrier lever, a link connecting the looper lever with the needle actuating lever, and connections for rocking the rock shaft from the needle actuator lever.

5. A stitch forming mechanism having, in combination, an under needle carrier, a looper, a looper lever on the upper end of which the looper is carried, a carrier lever having a transverse horizontal pivot on which the looper lever is mounted to swing to take the loop from the upper needle, an actuator connected to reciprocate the needle carrier, connections from the actuator to the looper lever, and separate connections from the actuator to the carrier lever to move the looper laterally.

6. A stitch forming mechanism having, in combination, an under needle carrier, an actuator lever connected to reciprocate the needle carrier, a looper, a vertical looper lever on the upper end of which the looper is carried, a carrier lever having a transverse pivot on which the looper lever is mounted, a link connecting the actuating lever to the looper lever, and means operated from the actuator lever for rocking the carrier lever.

7. A stitch forming mechanism having, in combination, an upper needle, an under needle, a looper, a vertical looper lever, a carrier lever mounted to swing on a horizontal axis and having a transverse horizontal pivot for the looper lever, an actuator, and separate connections from the actuator, for swinging the looper lever on its pivot and for rocking the carrier lever.

BERNARD T. LEVEQUE.
